CRACKING AND COOKING HYDROCARBON
OILS

Tom Williamson, Port Arthur, Tex., and Ned A. Scardino, Lockport, Ill., assignors, by mesne assignments, to The Texas Company, New York, N. Y., a corporation of Delaware

Application December 31, 1940, Serial No. 372,510

7 Claims. (Cl. 196—48)

This invention relates to the cracking and coking of hydrocarbon oils and contemplates a process in which the oil is heated to a cracking temperature and directed into a reaction zone wherein the oil is subjected to cracking conditions of temperature and pressure and wherein separation of vapors from liquid residue takes place and in which the liquid residue together with a portion of the vapors sufficient to effect coking is flash distilled to a coke residue, while the remaining vapors are separately withdrawn from the reaction zone and directed to a zone separate and apart from the coking zone. The invention is particularly adapted for the treatment of heavy stocks, such as topped or reduced crudes, and in accordance with the invention the heavy stock is combined with a stream of highly heated condensate stock for cracking in a cracking chamber and a mixture of residue and vapors is passed to the coking zone to accomplish reduction to a coke residue without priming in the coking zone.

The invention has particular reference to that type of pressure cracking and coking process in which a cycle condensate is passed through a heating coil wherein it is heated to a cracking temperature, the resultant heated stream combined with a heavy stock, such as a crude residual stock, and conversion of the commingled products carried on, and in which the residual products from the cracking operation are passed to a coking zone for conversion into coke. It has been found that when the total products from the reaction chamber, that is, all of the liquid and vaporous constituents, are delivered to the coking drum, that conversion to a coke residue may be accomplished, but such operation necessitates the maintenance of relatively low charging and recycling rates in order to avoid priming in the coking drum. The coking operation is usually carried on with a plurality of coke drums, one being on stream while the others are down for cleaning, and the priming operation is particularly troublesome in that portion of the run after having recently switched from one coke drum to another, the condensation occurring in the relatively cool drum apparently causing the accumulation of considerable quantities of liquid which soon give rise to extensive priming, due to the vapor volume and velocity of the stream entering the coke drum. When separation of vapors from liquid residue takes place in the cracking reaction chamber and when only the residue is passed to the coking chamber the autogenous heat of the residue is insufficient to effect coking. Even when withdrawing the products from the reac-

tion chamber at temperatures as high as 910° F. it has been found that the contained heat of the residue is insufficient to effect coking for the production of marketable coke. To overcome the heat deficiency in the residue resort has been had to the by-passing of a portion of the heated stream from the condensate heating coil into the coking drum, but this operation is disadvantageous because the reduction in the quantity of the heated stream for combining with the heavy stock or black oil has necessitated that such heavy stock or black oil be passed through a heating coil before combining with the cycle condensate stream.

We have found that by retaining only a portion of the vapors in the residue withdrawn from the reaction chamber that autogenous coking may readily be accomplished while avoiding priming in the coking drum. In accordance with our invention the heavy stock or black oil, such as topped or reduced crude, may be employed in dephlegmating the vapors from both the coking drum and the cracking reaction chamber, the resultant mixture of residual constituents and condensate is combined with the heated stream from the cycle condensate heating coil for cracking in a reaction chamber in which separation of vapors from liquid residue takes place and the residue is withdrawn together with sufficient vapors to maintain the desired coking temperature in the coking drum for conversion to a coke residue, while the remaining vapors are passed to a zone separate from the coking zone.

The practice of our invention, in which only that portion of the vapors which is required for coking is passed with the cracked residue to the coking zone, makes it possible to very materially increase the recycling rate without coke drum priming. The increase in the rate of cycle condensate passed to the heating coil is accompanied with certain important technical effects. By decreasing the time factor in the heating coil a higher 90% distillation point and higher color can be maintained on the cycle condensate without coking difficulties; the increased recycling rate permits increased reaction chamber temperatures for the same soaking volume factor and coking limitation; increased reaction chamber temperatures result in a higher ratio of vapor passing to the dephlegmator in relation to the black oil being passed from the dephlegmator to the reaction chamber; and the resultant high reaction chamber temperature makes it possible to obtain sufficient heat for coking without drawing excessive

amounts of vapor along with the liquid to the coking drum.

The invention contemplates further the distribution of the vapors from the reaction chamber and coking drum in such a way as to inhibit coking in the dephlegmating or fractionating portions of the system while at the same time making possible the production of a heavy fuel oil product. In running to coke and fuel oil, in accordance with the invention, the vapors from the coking drum are subjected to primary fractionation or dephlegmation to produce a tarry condensate adapted for fuel oil, the uncondensed vapors passed to a fractionating zone into which the separated vapors from the reaction chamber are introduced and wherein the combined vapors are dephlegmated with charging stock such as topped or reduced crude, the resultant mixture of reflux condensate and unvaporized charging stock is combined with the highly heated stream from the cycle condensate heating coil for reaction in the reaction chamber, the uncondensed vapors are further fractionated, to obtain a desired distillate product such as gasoline and a super-clean condensate which is cycled to the heating oil, separation of vapors from liquid residue takes place in the reaction chamber and the liquid residue together with sufficient vapor for coking is passed to the coking drum.

In running to coke only, in accordance with the invention, the vapors from the coking drum are subjected to primary fractionation or dephlegmation, the uncondensed vapors combined with separated vapors from the reaction chamber and subjected to dephlegmation with the charging stock, the resultant mixture of reflux condensate and unvaporized charging stock is then passed to the primary dephlegmating zone to dephlegmate the vapors therein and the final mixture of reflux condensate and unvaporized charging stock is combined with the highly heated stream from the condensate heating coil for reaction in the reaction chamber.

For the purpose of more fully explaining the invention reference is now had to the accompanying drawing which is a diagrammatic sectional elevation of an apparatus adapted for the practice of the invention.

In practicing the invention cycle condensate from a source hereinafter explained is heated to a cracking temperature in a heating coil 10 mounted in a suitable furnace 11, and the heated products pass through a transfer line 12 to a reaction chamber 13 which is suitably heat insulated and wherein separation of vapors from liquid residue takes place. Liquid is prevented from accumulating in the reaction chamber 13 by the rapid withdrawal of all the liquid together with a portion of the vapors. The mixture is passed through line 14 and pressure reducing valve 15, thence to coking chamber 16 wherein the residue is converted to coke by means of its contained heat. In practice a plurality of coke drums are employed so that while one is on stream the other or others may be down for cleaning and thus continuity in the complete process is maintained.

In accordance with the invention the separated vapors from the reaction chamber and from the coking chamber are admitted to different points in the fractionating or dephlegmating portion of the system so as to avoid coking difficulties which would be occasioned by the concentration of these highly heated vapors at one point. As shown in the drawing a dephlegmator or fractionator 17 is

provided having an upper section 18 and a lower section 19 separated by a condensate tray 20. Vapors from the coking drum 16 pass through a line 21, in which may be positioned a valve 22, to the dephlegmating section 19 which is conveniently supplied with baffles such as disc and doughnut elements 23. The separated vapors from the reaction chamber 13 pass through a line 24 and pressure reducing valve 25 to the fractionating section 18 which may also be equipped with suitable disc and doughnut trays 26. A valved run back line 41 may be provided for conducting liquid from the trapout tray 20 to the dephlegmating section 19 for refluxing 15. therein.

Charging stock is introduced by a pump 27 through a line 28 to the fractionating section 18 being preferably admitted to the upper portion of the tower 17. The charging stock serves to 20 dephlegmate the vapors from the reaction chamber as well as the uncondensed coke still vapors from section 19. The commingled reflux condensate and unvaporized charge is withdrawn from the tray 20 through a line 29 and is directed 25 by a pump 30 through a line 31 to the transfer line 12 or to the reaction chamber 13.

When running to coke and distillate fuel oil the valve in the run back line 41 is closed and all the liquid collecting on the tray 20 may be 30 directed by the pump 30 to the heater transfer line 12 or reaction chamber 13 while the fuel oil is withdrawn through a line 40. When running to coke only the valve in run-back line 41 is open so that the mixture of reflux condensate and 35 unvaporized charging stock may flow into dephlegmator 19 to dephlegmate the vapors therein and form a final mixture of reflux condensate and unvaporized charging stock which may be passed through a line 40 and a by-pass line 42 40 to the line 29 and thence through pump 30 and line 31 to the heater transfer line 12 or reaction chamber 13. In the coke only operation the trapout tray 20 is unnecessary but in such operation it is desirable to introduce the vapors from the 45 coking drum to a lower portion of the tower 17 and subject the vapors to dephlegmation and then combine the dephlegmated vapors with the separated vapors from the reaction chamber 13 for dephlegmation.

Uncondensed vapors from the tower 17 pass through a vapor line 32 to a fractionating tower 33 which is conveniently equipped with bubble trays 34 and which may be supplied with conventional cooling or refluxing means not shown. 55 Reflux condensate is drawn from the tower 33 by a pump 35 and directed through a line 36 to the heating coil 10. The uncondensed vapors pass from the tower 33 to a condenser 37 which discharges into a distillate receiver or gas separator 38 wherein the distillate product is collected. A portion of the reflux condensate from tower 33 may be passed through a cooler 43 and directed by a pump 44 through a line 45 to the dephlegmating section 19 to provide reflux therefor.

When running to coke and fuel oil the tarry condensate which collects in the dephlegmating section 19 may be withdrawn as a fuel oil product through the line 40. This product may be 70 flash distilled to produce a final fuel product of any desired gravity or flash test, while the flashed distillate may be refluxed in the fractionators.

In the drawing the cracking chamber 13 is shown as an up-flow chamber, although a down-flow chamber may also be employed in the prac-

tice of the invention. In the downflow operation the products from transfer line 12 including the black oil from line 31 may be introduced at the top of the reaction chamber and flow downwardly therein, the mixture of liquid residue and vapors being withdrawn from the bottom of the chamber, while the separate stream of vapors is withdrawn from a lower intermediate portion of the chamber above the point of residue withdrawal. While the downflow operation has an advantage in providing good contact between the constituents from the heating coil 10 and the black oil stream there is a tendency for the separate vapor stream to contain quantities of entrained tarry material. In another method of operation contemplated the products from transfer line 12 including the constituents from line 31 are admitted into a downflow reaction chamber in which liquid is prevented from accumulating and the products from which pass to a succeeding upflow chamber, the separate stream of vapors being taken off from the top of the upflow chamber to the fractionating section 18 and the mixture of liquid residue and vapors being withdrawn from the bottom of the upflow reaction chamber and passed to the coking drum 16. When operating with the upflow chamber, as illustrated, it is advantageous to spray the wall of the chamber with a portion of the reflux condensate from tower 17.

In practicing the invention the superclean cycle condensate from fractionator 33 is subjected to cracking at temperatures of the order of 1,000 to 1050° F. preferably under reasonably high pressures such as 400-800 lbs. in the heating coil 10 and upon being commingled with the black oil stream is subjected to cracking in the reaction chamber at temperatures in excess of 900° F. under superatmospheric pressures such as 300-600 lbs. Liquid is prevented from accumulating in the reaction chamber, the mixture of liquid and vapors being rapidly withdrawn and passed to the coking chamber while the separate vapor stream is passed to the fractionating portion of the system. A temperature approximating 910° F. is recommended for the mixture of vapors and residue in the line 14, with the temperature in the reaction chamber being somewhat higher. Although the pressure is reduced in the coking drum it is recommended that superatmospheric pressures of approximately 100 lbs. or higher be maintained therein; with pressures of 350 to 400 lbs. in the reaction chamber pressures of about 150-175 lbs. are very satisfactory in the coking drum. The major portion of the vapors from the reaction chamber flows through the vapor line while only a minimum proportion of the vapors is needed for admixture with the residue to accomplish the coking thereof. The quantity of vapors required to be included in the residue being withdrawn to accomplish coking is dependent upon the temperature in the reaction chamber and it is desirable to maintain as high a temperature as possible in the reaction chamber to keep the quantity of vapor withdrawn with the residue at a minimum. Ordinarily, a quantity of vapor of the order of 10%-20% of the amount of vapors flowing from the reaction chamber will be found adequate to accomplish coking without priming. The amount required can readily be controlled by observing the temperature in the transfer line to the coking drum or in the coking drum itself. The temperature required for coking will vary with the pressure used in the coking operation and somewhat with the character

of the stock. The temperature will generally be in excess of 825° F. and normally will be approximately within a range of about 840° F. to 885° F. A temperature of 850° F. under 150-175 lbs. pressure has been found very satisfactory. Under the conditions outlined coking is readily accomplished to yield a marketable coke while avoiding priming from the coke drum. The pressure in the dephlegmator or fractionator 17 will be approximately the same as that in the coke drum or if desired somewhat lower. When running to coke only, that is, when passing the mixture of reflux condensate and unvaporized charging stock from the dephlegmator 19 to the reaction chamber, it is desirable to maintain a temperature in the bottom of the dephlegmating section 19 as high as practicable without coking therein. Temperatures as high as 810-820° F. in the bottom of section 19 have been successfully employed. When running to coke and fuel oil; i. e., when withdrawing from the system the bottoms from dephlegmator 19 and directing the liquid from tray 20 to the reaction chamber it is generally necessary to maintain somewhat lower temperatures in dephlegmator 19, such as 790° F.-800° F. It is ordinarily desirable to introduce a cooling reflux, such as a portion of the cycle condensate conducted through line 45, into the upper portion of the dephlegmating section 19 in order to prevent coking as well as to remove tarry entrained material in the vapors.

The charging stock which is most advantageously a topped or reduced crude, after such preheating as may be desired, is introduced into the dephlegmating section 18 to dephlegmate the coke still vapors flowing upwardly from section 19 and the vapors from the reaction chamber entering through line 24. Gas oil constituents contained in the crude are distilled over into the tower 33. The unvaporized residual constituents together with the reflux condensate formed in section 18 are collected in tray 20 at temperatures of the order of 800° F.-815° F. for passage to the reaction chamber for cracking therein. The practice of the invention is particularly adapted for the treatment of crude stocks containing maximum quantities of gas oil. For the lighter stocks containing large proportions of gas oil such for example as 26-28 A. P. I. gravity topped crudes pressure approximating 400 lbs. are recommended for the reaction chamber while with heavier stocks such as a 20 A. P. I. gravity reduced crude the pressure should preferably be lowered to about 200 lbs.

The vapors pass overhead from the tower 17 at temperatures approximating 710° F.-730° F. to the tower 33 which may be maintained at approximately the same pressure as that of the tower 17, although somewhat lower pressures may be satisfactorily employed; thus, for example, with a pressure of 150 lbs. in the tower 17 the tower 33 may be held under a pressure of 135 lbs. The temperature in the bottom of the tower 33 approximates 660° F.-680° F. The top temperature in the tower is controlled to take off the distillate of the end point desired; thus, a temperature of 390° F. under 135 lbs. pressure may be employed in taking off a 400 end point gasoline distillate.

In a typical example of the invention a 25.6 gravity A. P. I. paraffin base reduced crude was charged to the fractionator 18 at a rate of 192 barrels per hour, cycle condensate was delivered from fractionator 33 to the cracking coil 10 at a rate of 477 barrels per hour and the black oil was passed from the tray 20 to the reaction chamber

at the rate of 280 barrels per hour. The outlet temperature of the cracking coil was 1035° F. An upflow reaction chamber was employed with a pressure of 400 lbs., with a top temperature of 909° F. and a bottom temperature of 915° F. The coking drum was held at 842° F. under 150 lbs. pressure. A distillate fuel oil product was withdrawn from the dephlegmator 19.

In a second example of the invention with a 26.2 gravity A. P. I. reduced crude a downflow reaction chamber was employed, the charge was introduced at a rate of 166 barrels per hour, the recycle rate to the cracking coil was 479 barrels per hour, and the black oil recycle rate was 235 barrels per hour. The temperature of the cracking coil outlet was 1015° F. The reaction chamber was under 400 lbs. pressure and the mixture of vapors and residue was withdrawn from the reaction chamber at a temperature of 910° F. The coke drum was under 175 lbs. pressure and at a temperature of 843° F. A distillate fuel product was withdrawn from the primary dephlegmator.

In a third example of the invention a reduced crude of the same gravity was reduced to coke with no distillate fuel product being made. The charge was introduced at a rate of 124 barrels per hour, the recycle rate to the cracking coil was 446 barrels per hour, and the black oil was passed from dephlegmator 19 to the reaction chamber at a rate of 210 barrels per hour. The cracking coil outlet was at a temperature of 1010° F. A downflow reaction chamber was employed being maintained under 400 lbs. pressure and the mixture of vapors and residue was withdrawn from the reaction chamber at a temperature of 909° F. The coke drum was under 175 lbs. pressure and at a temperature of 845° F.

In these runs a yield of about 55%-59% of gasoline having an octane value of 74-77 C. F. R. R. was obtained. In the first and second runs a yield of about 15% of distillate fuel oil was produced.

Prior to applicants' invention it had not been possible to operate to coke and distillate fuel oil simultaneously without having to heat the black oil in a separate furnace coil. The practice of the invention has made it possible to run to coke and distillate fuel oil simultaneously with charging rates of the order of 180-200 barrels per hour. The practice of the invention has made it possible when running to coke only to raise the charging rate from about 80 barrels per hour up to 125 barrels per hour, effecting an increase in capacity of 55% without any reduction in gasoline yield, and in fact, on some units the invention has made it possible to increase the charging rate to 140 barrels per hour, effecting an increase of 75% in capacity, also without reduction in gasoline yield.

In accordance with the invention, it is possible to include sufficient vapor with the residue withdrawn from the reaction chamber to furnish sufficient heat for coking and yet have the total coking drum input well below the priming point even at capacities of 200% or more over the previous capacity. Previously, for example, when operating on topped paraffin base crude at recycle rates, that is, the rates of cycle condensate passed to the heating coil, above about 280 barrels per hour priming occurred in the coke drum which limited the charging rate to about 85 barrels per hour. Prior to applicants' invention the limits on the recycling rate, that is, the rate of cycle condensate passed to the heating coil were

found to be with various stocks approximately within the range of 230 to 280 barrels per hour. The practice of the invention enables the increasing of the recycle rate up to high rates approximating 400-500 barrels per hour. In view of the high recycle rate made possible by the invention it is particularly adapted for the processing of light topped crudes containing large proportions of gas oil.

10 Although a preferred embodiment of the invention has been described herein, it will be understood that various changes and modifications may be made therein, while securing to a greater or less extent some or all of the benefits of the 15 invention, without departing from the spirit and scope thereof.

We claim:

1. In the conversion of higher boiling hydrocarbon oils into lower boiling ones, the process 20 that comprises passing cycle condensate through a heating zone wherein it is heated to a cracking temperature, combining the resultant heated products with a residual stock for cracking in a reaction zone wherein separation of vapors from liquid residue takes place, maintaining cracking temperatures of the order of upwards of 900° F. under superatmospheric pressure in the reaction zone, preventing the accumulation of liquid residue therein, withdrawing the liquid residue from 25 the reaction zone together with a portion of the vapors sufficient to support autogenous coking and amounting to a proportion of the order of 10-20% of the vapors flowing from the reaction zone, delivering the mixture of liquid residue and 30 vapors to a lower pressure coking zone to thereby effect coking solely by the contained heat of the mixture, separately withdrawing separated vapors from said reaction zone, separately dephlegmating the evolved vapors from the coking zone to form a tarry condensate subjecting the dephlegmated vapors and the vapors separately withdrawn from said reaction zone to fractionation to separate reflux condensate from lower 35 boiling products and directing resultant reflux condensate to the aforesaid heating zone.

2. In the conversion of higher boiling hydrocarbon oils into lower boiling ones, the process 40 that comprises passing cycle condensate through a heating zone wherein it is heated to a cracking temperature, combining the resultant heated products with oil for cracking in a reaction zone wherein separation of vapors from liquid residue takes place, maintaining cracking temperatures of the order of upwards of 900° F. under 45 superatmospheric pressure in the reaction zone, preventing accumulation of liquid residue therein, withdrawing the liquid residue from the reaction zone together with a portion of the vapors sufficient to support autogenous coking and 50 amounting to a proportion of the order of 10-20% of the vapors flowing from the reaction zone, delivering the mixture of liquid residue and vapors to a lower pressure coking zone to thereby effect 55 coking solely by the contained heat of the mixture, separately withdrawing separated vapors from said reaction zone, primarily dephlegmating the evolved vapors from the coking zone to form a tarry condensate, passing the uncondensed vapors to a subsequent dephlegmating zone, introducing the separately withdrawn vapors from 60 said reaction zone directly to said subsequent dephlegmating zone, introducing charging stock into said subsequent dephlegmating zone, withdrawing the resultant mixture of condensate and 65 unvaporized charging stock from said subsequent 70 dephlegmating zone.

75

dephlegmating zone and utilizing the mixture as the oil combined with the heated products from the heating zone for cracking in the reaction chamber as aforesaid, subjecting vapors uncondensed in said subsequent dephlegmating zone to further fractionation to separate a distillate product from a higher boiling reflux condensate and directing said reflux condensate to the aforesaid heating zone.

3. In the conversion of higher boiling hydrocarbon oils into lower boiling ones, the process that comprises passing cycle condensate through a heating zone wherein it is heated to a cracking temperature, combining resultant heated products with oil for cracking in a reaction zone wherein separation of vapors from liquid residue takes place, maintaining cracking temperatures of the order of upwards of 900° F. under superatmospheric pressure in the reaction zone, preventing accumulation of liquid residue therein, withdrawing the liquid residue from the reaction zone together with a portion of the vapors sufficient to support autogenous coking and amounting to a proportion of the order of 10-20% of the vapors flowing from the reaction zone, delivering the mixture of liquid residue and vapors to a lower pressure coking zone to thereby effect coking solely by the contained heat of the mixture, separately withdrawing separated vapors from said reaction zone, dephlegmating separated vapors from the coking zone and reaction zone with charging stock, utilizing the resultant mixture of reflux condensate and unvaporized charging stock as the oil combined with the heated products from the heating zone for cracking in said reaction zone, subjecting the uncondensed vapors to further fractionation to separate a distillate product from higher boiling reflux condensate and directing said reflux condensate to the aforesaid heating zone.

4. In the conversion of higher boiling hydrocarbon oils into lower boiling ones, the process that comprises passing cycle condensate through a heating zone wherein it is heated to a cracking temperature, combining resultant heated products with oil for cracking in a reaction zone wherein separation of vapors from liquid residue takes place, maintaining cracking temperatures of the order of upwards of 900° F. under superatmospheric pressure in the reaction zone, preventing accumulation of liquid residue therein, withdrawing the liquid residue from the reaction zone together with a portion of the vapors sufficient to support autogenous coking and amounting to a proportion of the order of 10-20% of the vapors flowing from the reaction zone, delivering the mixture of liquid residue and vapors to a lower pressure coking zone to thereby effect coking solely by the contained heat of the mixture, separately withdrawing separated vapors from said reaction zone, subjecting the evolved vapors from the coking zone to dephlegmation in a primary dephlegmating zone, passing the uncondensed vapors from the primary dephlegmating zone to a secondary dephlegmating zone, introducing the separately withdrawn vapors from said reaction zone directly to said secondary dephlegmating zone, introducing charging stock into said secondary dephlegmating zone, passing the resultant mixture of reflux condensate and unvaporized charging stock from said secondary dephlegmating zone to said primary dephlegmating zone to dephlegmate vapors therein, utilizing the resultant mixture of reflux condensate and unvaporized charging stock formed in the pri-

mary dephlegmating zone as the oil combined with the heated products from the heating zone for cracking in said reaction chamber, subjecting vapors uncondensed in said secondary dephlegmating zone to further fractionation to separate a distillate product from a higher boiling reflux condensate and directing said reflux condensate to the aforesaid heating zone.

5. In the conversion of higher boiling hydrocarbon oils into lower boiling oils, the process that comprises passing a condensate stock through a heating zone wherein it is heated to a cracking temperature, combining resultant heated products with a residual stock for cracking in a reaction zone wherein separation into vapors and liquid residue takes place, maintaining cracking temperatures of the order of upwards of 900° F. under superatmospheric pressure in the reaction zone, separately withdrawing vapors from said reaction zone and subjecting them to fractionation, preventing the accumulation of liquid residue in said reaction zone, withdrawing the liquid residue from the reaction zone together with a portion of the vapors sufficient to support autogenous coking and amounting to a proportion of the order of 10-20% of the vapors flowing from the reaction zone, delivering the mixture of liquid residue and vapors to a lower pressure coking zone to thereby effect coking solely by the contained heat of the mixture, and separately dephlegmating the vapors from the coking zone to form a tarry condensate adapted for fuel oil and withdrawing said condensate as a product of the process.

6. In the conversion of higher boiling hydrocarbon oils into lower boiling ones, the process that comprises separately heating a residual stock and a condensate stock and combining the heated stocks at a cracking temperature for cracking in a reaction zone wherein separation of vapors from liquid residue takes place, maintaining cracking temperatures of the order of upwards of 900° F. under superatmospheric pressure in the reaction zone, preventing the accumulation of liquid residue in said reaction zone, withdrawing the liquid residue from the reaction zone together with a portion of the vapors sufficient to support autogenous coking and amounting to a proportion of the order of 10-20% of the vapors flowing from the reaction zone, delivering the mixture of liquid residue and vapors to a lower pressure coking zone to thereby effect coking solely by the contained heat of the mixture, separately dephlegmating the evolved vapors from the coking zone to form a tarry condensate, and subjecting the dephlegmated vapors and the vapors separately withdrawn from said reaction zone to fractionation to separate higher boiling condensate from lower boiling products.

7. In the conversion of hydrocarbon oils, the process that comprises passing cycle condensate to a heating zone wherein it is subjected to cracking conditions of temperature and pressure, delivering resultant heated products to a reaction zone maintained under cracking conditions of temperature and pressure and wherein separation of vapors from liquid residue takes place, preventing the accumulation of liquid residue therein by rapidly withdrawing the liquid together with a portion of the vapors, passing the separated vapors to a primary fractionating zone, directing the withdrawn mixture of liquid and vapors to a separating zone wherein separation of vapors from residue takes place, dephlegmating the separated vapors, passing the dephlegmated vapors to said primary fractionating zone, introducing

charging stock to the primary fractionating zone to dephlegmate the vapors therein, withdrawing a resultant mixture of reflux condensate and unvaporized charging stock from the primary fractionating zone and combining the mixture with the aforesaid heated products for cracking in said reaction zone, passing vapors from the

5 primary fractionating zone to a secondary fractionating zone wherein the vapors are fractionated to separate lighter products from higher boiling reflux condensate and directing said reflux condensate to the aforesaid heating zone.
